United States Patent Office.

HENRY WOLF, OF DETROIT, MICHIGAN.

Design No. 3,008, dated April 21, 1868.

DESIGN FOR ORNAMENTING TRUNKS, &c.

The Schedule referred to in these Letters Patent and making part of the same.

TO ALL WHOM IT MAY CONCERN:

Be it known that I, HENRY WOLF, of the city of Detroit, in the county of Wayne, and State of Michigan, have originated and designed a new Pattern or Design for Placing upon Trunks and Valises; for a full, clear, and exact description of which, reference is hereby made to the accompanying drawings making a part of this specification.

What I claim as my invention, and desire to secure by Letters Patent, is—

The design or pattern to be used in ornamenting trunks and valises, as herein set forth and shown.

HENRY WOLF.
